E. M. Mann

UNITED STATES PATENT OFFICE

GEORGE E. COOK, OF NEW YORK, N. Y.

MIXING DEVICE

Application filed August 10, 1931. Serial No. 556,179.

The invention relates to a mixing device, and more particularly to mixing device for carburetors.

Object:

5 Among the principal objects the invention has in view are: to provide means for more effectively and more quickly vaporizing the fuel mixture passing into an internal combustion engine; to take full advantage of the 10 heat present in the intake manifold; to force the fuel into direct contact with the walls of the intake manifold; to augment the breaking influence exerted upon the fuel by a mechanical device with a cross-current of incoming air; to provide a device which is 15 readily attached, which has no moving parts, which is permanent and which requires no alteration in the construction in the manifold or carburetor; to secure simplicity of construction and operation; and to obtain other 20 advantages and results as may be brought out in the following description.

In the drawing:

Figure 1 is a sectional view of a portion 25 of a carburetor and intake manifold of an internal combustion engine with my invention mounted in place therebetween;

Figure 2 is a plan of the invention;

Figure 3 is a sectional view on line 3—3 of 30 Figure 2; and

Figure 4 is a sectional view taken on line 4—4 of Figure 2.

In the description:

In the specific embodiment of the invention 35 illustrated in said drawing, the reference numeral 10 indicates a substantially flat body portion having very much the shape of a gasket, such as would be included between the flange 11 of an intake manifold 12 for an 40 internal combustion engine and a similar flange 13 on a carburetor of which a portion 14 is shown in the drawing. The said body portion in use is included flatwise between the said flanges with a gasket 15 below the said 45 body portion but preferably with no gasket above the body portion. The flanges, gasket and body portion are then secured flatwise together by the usual bolts 16.

The said body portion 10 aside from having 50 holes 17 near its opposite ends for pas-

sage of bolts therethrough, has a middle opening or passage 18 adapted to register with the interior passage formed by the carburetor and intake manifold. Across the middle opening 18 is a bridge or support 19 55 which may conveniently be stamped out of the same metal forming the body portion and twisted or bent to a transverse position above the plane of the body portion. On this bridge is mounted a deflect 20 which is preferably 60 circular in plan and of smaller diameter than the inside diameter of the intake manifold. The underside of this deflector preferably slopes upwardly outward in order that fuel will be deflected from the middle of the manifold toward the side wall thereof. The deflector provides a downwardly extending stem 21 which is permanently mounted upon the said bridge in fixed relation to the body 65 portion. 70

By the construction so far described, I provide mechanical means for interrupting the passage of fuel for purposes of more thoroughly mixing the same and diffusing or breaking up the stream of fuel in passing 75 into the intake manifold. The construction is such that the fuel is also deflected from the center of the manifold toward the side walls thereof, and as the side wall of the intake manifold of an internal combustion engine 80 becomes hot in use, the fuel is vaporized very quickly and effectively by forced contact with the said wall. This vaporization is conclusive of less fuel loss and greater efficiency in 85 the engine.

Additional means may be provided for breaking up the fuel stream, and for that purpose I have shown the upper face of body portion 10 provided with grooves 22 from the outer edge thereof to the middle opening 18. A limited air jet may therefore be drawn into the fuel passage through these grooves and the cross-current thus set up by the air jets will have a beneficial effect in breaking up the fuel stream and aiding in the vaporization process. 95

I claim:

A device as characterized comprising a substantially flat body portion adapted to be positioned between the flanges of an intake 100

manifold and a carburetor, said body portion having a middle opening, grooves in the body portion extending from the outer edge to the said middle opening to permit entry
5 of air therethrough, an upwardly projecting support extending from and integral thereto and centrally positioned from said body portion, and a deflector having a downwardly extending stem adapted to be mounted on
10 said support, and said deflector at its underside sloping upwardly outward so that fuel from the said manifold and air from the grooves will deflect the fuel from the middle
15 of the manifold towards the side wall thereof.
